ENGINE MOUNTING

Paul Charles Albert Marie d'Aubarède,
Saint-Genis-Laval, FranceApplication May 20, 1935, Serial No. 22,481. In
France May 19, 1934

13 Claims. (Cl. 180—64)

(Granted under the provisions of sec. 14, act of
March 2, 1927, 357 O. G. 5)

The invention refers to the mounting on a support of an engine with reciprocating parts, the power of said engine being derived therefrom through driving shafts at an angle with respect to the motor shaft which is connected with the reciprocating parts, this motor shaft, the driving shafts and the intermediate gearing being wholly supported by the engine assembly itself. An example of such an arrangement of parts 10 is the engine assembly for front drive cars, wherein the power is transmitted to the wheels by means of transverse driving shafts.

The mounting according to this invention is an application of the invention described in my U. S. 15 Letters Patent No. 2,055,279 dated September 22, 1936, filed April 15, 1933. It has been explained in this patent that under the action of the internal periodic forces and torques to which it is submitted the engine assembly tends to oscillate about variable natural oscillation axes.

20 But in a machine of the kind referred to the oblique position of the driving shafts with respect to the motor shaft produces a transverse torque on the engine assembly. The latter tends to rotate or oscillate about a further transverse axis and the mounting must be such as to prevent it from rotating while permitting its oscillations about the corresponding natural axis.

A first object of this invention is therefore to 30 dispose a flexible connection between an engine and its support that it will substantially permit oscillation about three natural oscillation axes, to wit, the oscillation axis corresponding to the internal periodic torques parallel to the motor 35 shaft or crankshaft, the oscillation axis corresponding to the internal periodic forces, and the oscillation axis corresponding to the periodic portion of the transverse driving torque.

A further object of this invention is to 40 dispose supporting springs for the engine on its support in such a way that they will permit oscillation about the natural oscillation axes while maintaining the engine against the action of the average driving torque.

45 Another object of this invention is to provide a flexible connection which will be of a sufficiently yielding character to accommodate variations in the position of the natural oscillation axes.

50 The elasticities and moments of inertia of the intermediate gearing between the motor shaft and the driving shafts are preferably so determined that this gearing forms an arresting filter between the motor shaft and the driving shafts.

55 The driving torque applied to the latter shafts is

thus as steady and regular as possible and the periodic portion of the transverse torque applied to the engine assembly is as reduced as possible. The tendency of the engine assembly to oscillate about the corresponding transverse natural axis is much reduced and the mounting is easier and more efficient.

The condition to be fulfilled by a torsional elastic system inserted in the gearing for obtaining the arresting filter operation is as follows:

$$a \geq \frac{C(\frac{2}{M} + \frac{1}{A})}{\omega_0^2}$$

in which:

a is the angle of twist of the torsional elastic system inserted in the gearing under the action of an average torque C on the motor shaft.

M is the moment of inertia of a supposed flywheel which, if keyed on the engine side of the torsional elastic system, would have a kinetic energy equal to the total kinetic energy of all the parts connected with this side of the system.

A is the moment of inertia of a supposed flywheel which, if keyed on the other side of the torsional elastic system, would have a kinetic energy equal to the total kinetic energy of all the parts connected with this side of the system.

It is assumed in the relation that the two sides of the torsional elastic system rotate at the same speed.

ω_0 is the smallest possible pulsation of the periodic torque of the engine.

In most cases, such a torsional elastic system is preferably disposed between the flywheel and the gear box.

The angular elastic reaction of the system, i. e. the rate of increase of the torque C with respect to the angle of twist a preferably increases with the torque C itself.

In the annexed drawings:—

Fig. 1 is a side view of a mounting according to this invention applied to an engine assembly for cars or the like, the engine being of the standard pattern.

Fig. 2 is a plan view thereof.

Fig. 3 is an end view.

Fig. 4 is a detailed vertical section of the abutment to an enlarged scale.

Figs. 5 to 7 show in the same manner a modified form of mounting according to this invention.

Fig. 8 shows a modified form of connecting member.

Figs. 9 and 10 are side views showing other

modifications of a mounting according to this invention.

Figs. 11 to 13 show some further examples of connecting members.

Fig. 14 is a side view showing a mounting according to this invention applied to an engine assembly for vehicles or the like, in which the engine cylinders are radially arranged in a horizontal plane.

10 Fig. 15 is a plan view thereof.

Fig. 16 shows a modified form of spring.

Fig. 17 is an end view of a torsional elastic system.

Fig. 18 is a longitudinal section thereof.

15 Figs. 19 to 21 show another example of such a torsional system.

Figs. 22 to 24 show modified forms thereof.

Fig. 25 is a transverse section of another torsional elastic system.

20 In the drawings, the engine assembly comprises an internal combustion engine 1. The crank-shaft axis is indicated at V—V and there is provided a gear box 2 which connects the crankshaft with the transverse shafts 3. The latter directly drive the wheels of the car (the front wheels, for instance). They are perpendicular to the crank-shaft axis V—V. The center of gravity is shown at G and F designates the line of action of the resultant of the periodic forces.

30 The engine assembly is submitted to three principal different stresses:

1. The internal periodic forces which tend to oscillate the engine assembly about an axis such as c—c.

35 2. The internal periodic torque of the engine proper (torque exerted by the crankshaft on the flywheel) which tends to oscillate the engine assembly about a longitudinal axis such as X—X, passing through G and substantially parallel to V—V.

The actions of these forces and torques have been explained in my above-referred to patent application No. 686,380.

40 3. A transverse torque or driving torque resulting from the torque exerted by shafts 3. This torque is not wholly regular and comprises a periodic portion which tends to oscillate the engine assembly about a transverse axis T—T passing through G.

50 The mounting according to this invention is so arranged that the engine assembly is free to oscillate about its natural oscillation axes c—c, X—X and T—T, notwithstanding their variations in position.

55 In the arrangement according to Figs. 1, 2 and 3, the engine assembly is supported by two lateral springs 4 and 5 and it is attached to the frame 7 by means of a flexible connection. The latter comprises a block 6 of rubber or the like glued between a bracket 8 fixed to the gear box 2 and a plate 9 fixed to the frame 7. The engine is thus free to oscillate about a variable axis intermediate between c—c and T—T owing to the yielding character of block 6. It is also free to oscillate about a longitudinal axis such as X—X.

60 Springs 4 and 5 support a part of the weight of the engine. They have also to resist the average driving torque exerted by shafts 3 and the eventual average torque exerted by the crank-shaft on the flywheel (during accelerations).

70 The end of the engine remote from the connection 6—7—8—9 is provided with a limiting abutment detailed in Fig. 4. It comprises a rubber block 10 glued on a hollow finger 11 fixed to the

engine proper 1 by bolts 12. Block 10 is housed with play within a slightly conical box 13 fixed to the frame 7. When, under external actions (jolts on the road, for instance) the engine tends to move more than normal with respect to the frame, block 10 limits the motion. The length of finger 11 is smaller than the thickness of block 10 and therefore the contact between block 10 and box 13 is very progressive, since it begins at 14, where the rubber is unsupported.

10 The play of block 10 within box 13 is preferably adjustable by means of a flexible strip 100 pressed by an adjusting screw 101.

15 In the mounting according to Figs. 5, 6 and 7 the flexible connection embodies a tubular block 15 of soft rubber arranged between a transverse hole through the engine casing and a rod 16 supported by arms 17 fixed to the frame. There are provided two lateral springs 18 and 20 and an axial one 19. There is also provided a limiting abutment of the kind shown in Fig. 4.

20 This mounting is similar to the preceding one. Spring 18 relieves the flexible connection 15—16 of the engine weight, provided, of course, the respective strengths of the springs are correctly determined with respect to distances a and b (Fig. 6).

25 Fig. 8 shows a modified type of connection in which rod 16 is located between two soft rubber blocks 21, 22 within a stirrup 23 fixed on the gear box 2. Abutments 24 and 25 (made of fibre or the like) limit the vertical motions of the engine with respect to rod 16. This connection is appropriate when, as in Figs. 5 to 7, the engine is wholly supported by springs.

30 In the mounting according to Fig. 9, the flexible connection between engine and frame consists of a supple strap 26. The engine assembly is supported by two springs 27 and 28 arranged together with the connection 26 and the abutment 10 in a substantially longitudinal vertical plane passing through G. The engine is free to oscillate about a transverse axis variable within wide limits; it is also maintained against the average driving torque exerted by shafts 3. Concerning the torques which tend to oscillate the engine about a longitudinal axis parallel to the crank-shaft axis, it must be remarked that at constant engine speed there is no average torque of such axis tending to rotate (i. e. to overturn) the engine; there is a mere periodic torque tending to oscillate it, which is possible by twisting strap 26. The tendency of the engine to overturn therefore only occurs during sudden accelerations and the abutment 10—13 limits the angle of rotation, 40 block 10 and box 13 being rectangular or square in cross-section.

45 In the mounting of Fig. 10 there is but one spring 29 and a connection 30 comprising a soft rubber block 38 between metallic plates 31 and 32 with turned edges. Plate 31 supports the gear box 2 through two bolts 33 disposed each side of block 38. Plate 32 rests on the frame 7. Two auxiliary rubber blocks 34 are disposed between the turned edges of plates 31 and 32 to longitudinally retain the engine.

55 Fig. 11 shows a similar type of connection in the free state. Under the weight of the engine the central rubber block 35 is compressed between plates 36 and 37. The auxiliary blocks 38 then are compressed and assume a rectangular shape.

60 In the connection according to Fig. 12, the edges of plates 39 and 40 are oblique; thus when the connection is loaded, the auxiliary blocks 41 are more highly compressed.

In the connection shown in Fig. 13, there is only provided one main rubber block 42 to support the engine weight. The auxiliary blocks of Figs. 10, 11 and 12 are replaced by a flexible strap 43 attached to frame 1 and to a curved arm 44 fixed to the gear box 2. The main block 42 is itself comprised between plates 45 and 48. Curved wings 46 and 47 limit the flexion of strap 43 and turned edges 49 and 50 avoid an abnormal compression of the same.

In the mounting according to Figs. 14 and 15, the engine proper 1' is of the radial-cylinder type and the crankshaft is vertical. The gear box 2' is disposed beneath the crankcase. The internal periodic torques thus tend to oscillate the engine about an axis X—X passing through G and parallel to the axis V—V of the crankshaft. This axis X—X is practically located in the immediate vicinity of the latter, the engine assembly being almost symmetrical. The transverse periodic driving torque tends to oscillate the engine about the axis T—T passing through G and parallel to the transverse driving shafts 3'.

In such an engine the periodic forces are located in the plane F—F of the cylinder axes. The line of action of their resultant rotates in this plane, either in the same direction as the crankshaft or in the reverse direction, according to the construction of the engine.

When this resultant is not balanced by special devices, it tends to oscillate the engine assembly about an axis similar to axis c—c of Figs. 1 and 2, but rotating about X—X as the resultant proper, in such a manner that the engine assembly tends to move so to speak conically about a point C (Fig. 14) which is the intersection of X—X and c—c. Of course point C varies in position, as axis c—c itself, within certain limits.

The mounting comprises two spring systems disposed at each side of the engine, substantially in plane F—F. Each system is formed of two springs 71 inserted between an arm 72 fixed to the engine 1' and a forked member 73 fixed to the frame 1'. An adjusting screw 74 is provided to adjust the system.

The flexible connection is formed of a soft rubber block 75 fixed to the frame 1' and entering a recessed portion at the bottom of the gear box 2'. Owing to the yielding character of block 75, the engine assembly is free to oscillate about point C and also about axis T—T. The average driving torque is supported by springs 71 which prevent the engine from overturning about a transverse axis.

The limiting abutment 10—13 is placed at the top of the engine as shown.

Fig. 16 shows a modified form of spring system comprising but one spring 76 formed as a flat spiral inserted within a ring 77 fixed to the engine. The inner winding is fixed to a stud 78 carried by the frame. Spherically curved plates 79 are provided at each side of the spring in such a way that when the latter is deflected in either direction the windings progressively contact a plate and are inactive, whereby the elastic reaction increases with the load. Of course the plates may also be supported by ring 77 and cooperate with the outer windings instead of the inner ones; the increase in elastic reaction is practically more rapid with this second arrangement.

In the mountings described, the springs are preferably conical as shown, the windings being made of a flat steel strip. They have a variable elastic reaction, as explained in my patent ap-

plication No. 10,075 filed March 8, 1935. They are so determined that the oscillating system formed by the engine on its springs operates as an "arresting filter" for the periodic strains at any normal engine speed.

In all these mountings the operation is greatly improved when an elastic system is interposed in the transmission of power from the engine to the driving shafts. It has been explained that the engine (Fig. 1) tends to oscillate about axis c—c under the action of the internal periodic forces and about axis T—T under the action of the periodic portion of the driving torque (exerted by shafts 3). These tendencies result in an oscillation about a widely variable instantaneous axis whose position is dependent on the relative amplitudes and phases of each individual oscillation. By lessening as much as possible the importance of the periodic portion of the driving torque, the tendency to oscillate about T—T is decreased and the instantaneous axis practically remains in the vicinity of c—c.

In Figs. 17 and 18 a layer 51 of soft rubber or the like is inserted between two tubular coaxial members 52 and 53 provided with registering undulations as shown. Member 52 is fixed to the flywheel 54 keyed at the end of the crankshaft 55; member 53 is fixed on the driven shaft 56. Arcuate openings 57 are provided in member 53 and they cooperate with studs 58 to limitate the twisting of the device under abnormal stresses.

In the device according to Figs. 19, 20 and 21, the elastic material is inserted between two disk-like members 59 and 60 having slightly undulated surfaces.

Fig. 22 shows the same kind of device with undulations of greater depth, for transmitting higher torques.

In Fig. 23, the undulations of the disks have the same depth from the inner part to the outer periphery. A collar 65 formed at the end of the driving shaft 63 is retained by a flange 66 carried by the driven shaft 64.

In Fig. 24, the thickness of the elastic material decreases from the periphery down to the inner part.

The device of Fig. 25 embodies two hollow shafts 67 and 68 connected by elastic strips 69 and 70.

All these devices must be determined so as to fulfill the above-described condition:

$$a \geq \frac{c \left(\frac{2}{M} + \frac{1}{A} \right)}{\omega_0^2}$$

On the other hand, their elastic reaction preferably increases with the torque transmitted. Since an internal combustion engine never exerts its full torque at low speeds, the filter condition is always fulfilled notwithstanding the increase in hardness (elastic reaction) of the coupling provided, of course, that this increase be correctly determined.

In the above examples, the angle of the power shafts with respect to the motor shaft (crank-shaft) is 90°. This is the most common case. When the power shafts or shaft are at an angle other than 90° with respect to the crankshaft, the axis T—T has to be determined and the flexible connection has to be so selected and located as to permit the oscillation of the engine about such an axis.

In the above description the term "internal" as applied to the periodic torques or forces only

means that these torques and forces result from parts internal to the engine proper and is used for differentiating such forces or torques from the driving torque exerted by shafts 3.

5 I claim:—

1. In combination a frame; an engine assembly submitted to periodic internal forces and to periodic internal torques tending to oscillate it about two varying natural oscillation axes; a 10 motor shaft in said engine assembly; driving shafts through which a driving torque is derived from said engine assembly, said driving shafts being supported by said engine assembly at an angle with said motor shaft; spring means adapted to 15 maintain said engine assembly on said frame against gravity and against the action of the average driving torque exerted by said driving shafts; and a flexible connection between said engine assembly and said frame for yieldably retaining said engine assembly with respect to the 20 frame while permitting the engine assembly to oscillate so as to accommodate oscillatory motion of said engine assembly about the varying natural oscillation axes resulting from said internal 25 periodic forces, internal periodic torques and spring means, and also about an oscillation axis resulting from the action on said engine assembly of the periodic portion of the driving torque exerted by said driving shafts; said connection being disposed substantially on the average 30 position of the varying natural oscillation axis which is the resultant of the actions of the internal periodic torques and of the spring means, at a position intermediate between the 35 center of gravity of said engine assembly and the intersection of said last-named varying natural oscillation axis with said varying natural oscillation axis which is the resultant of the actions of the internal periodic forces and of the spring 40 means.
2. In combination a frame; an engine assembly submitted to periodic internal forces and to periodic internal torques tending to oscillate it about two varying natural oscillation axes; a 45 motor shaft in said engine assembly; driving shafts through which a driving torque is derived from said engine assembly, said driving shafts being supported by said engine assembly transversely of said motor shaft; spring means adapted to 50 maintain said engine assembly on said frame against gravity and against the action of the average driving torque exerted by said driving shafts; and a flexible connection for yieldably retaining said engine assembly with respect to the frame while permitting the engine assembly to oscillate so as to accommodate oscillatory motion of said engine assembly about the substantially longitudinal varying natural 55 oscillation axis of said engine assembly under the action of said internal periodic torques, and also oscillatory motion about a varying substantially transverse oscillation axis which is the resultant of the actions of said periodic internal forces, of said spring means and of the periodic portion of the driving torque exerted by said driving shafts; said connection being disposed substantially on the average position of the substantially longitudinal natural oscillation axis which is the 60 resultant of the actions of the internal periodic torques and of the spring means, at a position intermediate between the center of gravity of said engine assembly and the intersection of said last-named natural oscillation axis with the varying natural oscillation axis which is the 65

resultant of the actions of the internal periodic forces and of the spring means.

3. In combination a frame; an engine assembly comprising an engine proper with a row of substantially vertical cylinders and a crankshaft 5 longitudinally disposed under said row, said engine producing periodic torques tending to oscillate said engine assembly about a varying natural oscillation axis passing through the center of gravity thereof and parallel in average direction 10 to said crankshaft, and said engine also producing periodic forces tending to oscillate said engine assembly about a varying natural oscillation axis substantially transverse with respect to said first-named natural oscillation axis; driving shafts 15 through which a driving torque is derived from said engine assembly, said driving shafts being supported by said engine assembly transversely of said crankshaft; spring means adapted to maintain said engine assembly on said frame 20 against gravity and against the action of the average driving torque exerted by said driving shafts; and a flexible connection for yieldably retaining said engine assembly with respect to said frame, said connection being disposed substantially on the average position of said first-named varying natural oscillation axis, at a position intermediate between the center of gravity of said engine assembly and the average position of said second-named varying natural oscil- 25 lation axis.

4. In a combination as claimed in claim 3, said spring means comprising two spring systems disposed at each side of said engine assembly on the other side of the center of gravity of said 30 engine assembly with respect to said connection.

5. In a combination as claimed in claim 3, said spring means comprising two spring systems disposed at each side of said engine assembly on the other side of the center of gravity of said 40 engine assembly, with respect to said connection; and a third spring system in the vicinity of said connection; said three spring systems being so determined in strength as to relieve said connection of the weight of said engine assembly. 45

6. In a combination as claimed in claim 3, said spring means comprising two spring systems disposed at each side of said connection, said spring systems and connection being substantially disposed in the longitudinal vertical plane passing 50 through the center of gravity of said engine assembly, and said spring systems being determined so as to support substantially the whole weight of said engine assembly.

7. In a combination as claimed in claim 3, said spring means comprising a spring system disposed opposite to said connection with respect to the center of gravity of said engine assembly. 55

8. In a combination as claimed in claim 1, a limiting abutment adapted to limit the motions of said engine assembly with respect to said frame under other actions than those of the internal periodic forces and torques and of the driving torque.

9. In a combination as claimed in claim 1, a 65 limiting abutment adapted to limit the motions of said engine assembly with respect to said frame under other actions than those of the internal periodic forces and torques and of the driving torque; said abutment comprising a rubber member on the engine, a box on the frame housing said rubber member with play, and an adjustable plate within said box to limit the degree of freedom of said rubber member. 70

10. In a combination as claimed in claim 3, said 75

spring means being so disposed as to relieve said flexible connection from the weight of said engine assembly; and said flexible connection comprising a transverse rod fixed to the frame, a stirrup fixed to said engine assembly and traversed by said rod, and rubber blocks interposed between the sides of said rod and the sides of said stirrup.

11. In a combination as claimed in claim 3, said spring means being so disposed as to relieve said flexible connection from the weight of said engine assembly; and said flexible connection comprising a transverse rod fixed to the frame, a stirrup fixed to said engine assembly and traversed by said rod, rubber blocks interposed between the sides of said rod and the sides of said stirrup, and blocks forming abutments to limit vertical motion of said rod within said stirrup.

12. In a combination as claimed in claim 3, said spring means being so determined that said flexible connection supports a part of the weight of said engine assembly; and said flexible con-

nection comprising a block of rubber to support the said part of the weight of said engine assembly; and said flexible connection comprising a block of rubber to support the said part of the weight of said engine assembly, vertical members fixed to the frame, vertical members fixed to said engine assembly, and blocks of rubber interposed between said frame and engine members to yieldably limit horizontal motions of said engine assembly with respect to said frame.

13. In a combination as claimed in claim 3, said spring means being so determined that said flexible connection supports a part of the weight of said engine assembly; and said flexible connection comprising a block of rubber to support the said part of the weight of said engine assembly, and a horizontally disposed strap to prevent horizontal motions of said engine assembly with respect to said frame.

PAUL CHARLES ALBERT
MARIE D'AUBARÈDE.
